(57) **CLAIM**

The ornamental design for a figure eight carabiner, as shown and described.

DESCRIPTION

FIG. 1 is a front perspective view of the figure eight carabiner according to my design;

FIG. 2 is a front view of my design;

FIG. 3 is a back view of my design;

FIG. 4 is a left view of my design;

FIG. 5 is a right view of my design;

FIG. 6 is a top view of my design;

FIG. 7 is a bottom view of my design; and,

FIG. 8 is a front perspective view of a second embodiment that differs from the first embodiment only in that it is made from a square stock rather than a rounded stock material.
